UNITED STATES PATENT OFFICE.

WILLIAM GEORGE SEILER, OF ETNA, PENNSYLVANIA.

FOUNTAIN-BRUSH.

1,071,471.

Specification of Letters Patent. Patented Aug. 26, 1913.

Application filed May 15, 1913. Serial No. 767,871.

To all whom it may concern:

Be it known that I, WILLIAM GEORGE SEILER, a citizen of the United States of America, residing at Etna, in the county of Allegheny and State of Pennsylvania, have invented certain new and useful Improvements in Fountain-Brushes, of which the following is a specification, reference being had therein to the accompanying drawing.

10 This invention relates to fountain brushes, and the primary object of my invention is to furnish a brush with a detachable reservoir or container having positive and reliable means, as hereinafter set forth, for feeding a detergent, as liquid soap, to the bristles of a brush, whereby the brush can be expeditiously used for cleansing a surface.

20 A further object of this invention is to provide a scrub brush with a simple, durable and inexpensive reservoir attachment that can be easily and quickly connected to a brush whereby a cleansing material can be supplied to another part of the brush.

25 With the above and other objects in view the invention resides in the novel construction, combination and arrangement of parts to be hereinafter specifically described and then claimed.

30 Reference will now be had to the drawing, wherein:—

Figure 1 is a side elevation of a brush in accordance with this invention, Fig. 2 is a plan of the same, and Fig. 3 is a cross sectional view of the brush.

35 Further describing my invention in detail with reference to the accompanying drawing, wherein like numerals denote corresponding parts throughout: 1 denotes a brush body provided with bristles 2 and at the ends of said body are vertical openings 3. The upper ends of the openings 3 are enlarged to provide seats 4, the purpose of which will presently appear.

40 The reference numeral 5 denotes a rectangular reservoir or container that has the bottom thereof provided with a tubular boss 6 adapted to extend into the opening 3 and rest upon the seat 4 thereof. One side of

7 to engage under the body 1 of the brush. The opposite side of the reservoir has an outwardly extending and depending bracket 8 provided with a set screw 9 having a clamping head 10 adapted to engage the body 1 of the brush and lock the reservoir thereon. Connected to the upper edge of the reservoir by a hinge 11 is a lid or cover 12 provided with a hinged hasp 13 adapted to engage the reservoir 5 whereby the lid 14 or cover 12 can be secured in a closed position. The lid or cover 12 permits of soft soap or a suitable detergent being placed within the reservoir. A follower 14 is placed in the reservoir upon the detergent and the lid or cover 12 is provided with a set screw 15 adapted to engage said follower, whereby the follower can be lowered to force a quantity of the contents of the reservoir through the opening 3 and onto the bristles of the brush.

45 With the device capable of fitting upon either end of a scrub brush it is apparent that the brush can be evenly worn and continuously used.

50 It is preferable to make the device of non-corrodible metal and while in the drawing there is illustrated a preferred embodiment of the invention, it is to be understood that the structural elements are susceptible to such variations and modifications as fall within the scope of the appended claims.

75 What I claim is:—

1. A brush having a body provided with openings, a reservoir clamped upon the body of said brush and having the bottom thereof provided with a tubular boss adapted to extend into one of the openings of said body, a hinged lid carried by said reservoir, a follower within said reservoir, and means carried by said lid for engaging said follower to force the contents of said reservoir through the boss thereof and the opening of said brush body.

2. A brush having a body provided with openings, a reservoir clamped upon the body of said brush and having the bottom thereof provided with a tubular boss adapted to extend into one of the openings of said body, a hinged lid carried by said reservoir, a fol-

lower within said reservoir, means carried by said lid for engaging said follower to force the contents of said reservoir through the boss thereof and the opening of said brush body, and means including a clamping screw for securing said reservoir to said brush body.

In testimony whereof I affix my signature in the presence of two witnesses.

WILLIAM GEORGE SEILER.
